UNITED STATES PATENT OFFICE.

WILLIAM W. GRISCOM, OF HAVERFORD COLLEGE, PENNSYLVANIA, ASSIGNOR
TO THE ELECTRICAL ACCUMULATOR COMPANY, OF NEW YORK.

SECONDARY BATTERY.

SPECIFICATION forming part of Letters Patent No. 400,842, dated April 2, 1889.

Application filed December 18, 1888. Serial No. 293,932. (No model.)

To all whom it may concern:

Be it known that I, WILLIAM W. GRISCOM, a citizen of the United States, and a resident of Haverford College, in the county of Montgomery and State of Pennsylvania, have invented certain new and useful Improvements in Secondary Batteries, of which the following is a specification.

My invention is an improvement in secondary batteries or accumulators.

The invention more particularly has reference to the arrangement of the plates in the cell, whereby they are supported at or near their center free from the bottom of the cell in a manner which facilitates the removal of one element without disturbing the other. I have also devised an improved form of connection for uniting adjacent cells of battery, which is constructed of a practically inoxidizable metal.

Heretofore others have united the several plates forming one element of a pair by strips of metal arranged upon opposite edges near the central height of the plates, and have provided the plates of the complementary element with projections upon opposite edges designed to rest upon and be supported by the strips of the first element. I have found this arrangement susceptible of improvement, because the weight of both elements is thus thrown upon the lower section of one series of plates, causing or tending to cause a curvature of the said plates between the lower edge and the central line of said plates.

My improvement, designed to obviate this difficulty, consists in supporting both elements at points on two opposite edges of the plates near the central vertical distance thereof. Each plate of an element is furnished with projections on its opposite edges near the central vertical distance; the series of plates of one element at this point are united on both edges by a strip of conducting material; two points of support are arranged

within the inclosing-cell upon opposite sides thereof, and the described element is placed in position resting upon these supports. A strip of insulating material is placed upon the projections; or upon the strip of conduct-

ing material forming part of the described element, and the second element of the battery, consisting of a series of plates electrically united at or near their upper edges and having projections upon opposite edges at or near the central vertical distance, is placed in position with the said projections resting upon the said strips of insulating material. The points of support for both these elements are arranged upon the interior of the cell upon two opposite sides. I prefer to construct these supports from slabs of insulating material mechanically united in a manner to secure them in a fixed position with respect to each other. The height or position of these supports and the location of the projections on the plates are so arranged and proportioned that the bottom edges of both series of plates are in the same plane somewhat elevated from the bottom of the cell. One series of plates are interleaved with the other series in the usual and well-known manner.

For the purpose of uniting two adjacent cells of battery I provide each battery with lugs or terminals having a screw-thread. These lugs are preferably equal sections of a screw, the section on one cell being a complementary part of the section on an adjoining cell, so that when the two sections are brought together a screw-threaded nut can be placed over both, firmly uniting them mechanically and electrically. I prefer to form each section to represent one-half of a truncated cone divided in the plane of its major axis and having a series of parallel grooves in its curved surface, so that when the two halves are united the grooves on one section register with the grooves on the other, forming a continuous helical groove from one end to the other. I then pass the nut over both sections, mechanically uniting them in a practically-perfect electrical contact.

The accompanying drawings illustrate my invention.

Figure 1 is a perspective view of the two elements as they are placed in the inclosing-cell, both supported at or near the center. Fig. 1^a is a view of the preferred form of insulating-support. Fig. 2 is a side view, one of

the plates being broken away. Fig. 3 is a plan view of the connecting device, and Fig. 4 is a sectional side view thereof.

P and N are two elements or "electrodes," 5 as they are sometimes called, each consisting of a series of plates of lead, with an active material, consisting of oxide of lead, applied thereto in the form of a paste. The plates of one element are interleaved with the plates 10 of the other element in a manner long well known. They are separated and insulated from each other by pins p. The plates of one element, P, have projections o upon opposite edges at points near their central vertical distance. These projections are united with strips of conducting material, as lead, e and d. Said plates are also united at or near their upper edge by a strip of conducting material, c. The plates composing the element N are 15 united at or near their upper edges by strips a and b, and at or near their central vertical distance there are projections n upon opposite edges.

SS are sections of insulating material, as slabs 20 of paraffined wood. They are about one-half the height of the cell, and are united by strips s s, which keep them in position. These supports S S are placed in the cell and the element P is placed in position with the projections o o and strips e d resting on them. Strips of insulating material, i, are then placed 25 on the strips e and d, and the element N is then placed in position, with its projections n n resting upon the strips of insulating material, i i, but supported by the supporting pieces S S.

It is to be observed that the height of the supports S S and the position of the projections o and n are so placed and proportioned 40 that the bottoms of the elements P and N are in substantially the same plane, but somewhat elevated from the bottom of the cell, while both elements are supported from points at or near their central vertical distance.

45 On the free ends of the strips b and c are located connections for uniting two cells together. I construct these connections of an inoxidizable metal or alloy, such as lead and antimony. The terminal of each cell is preferably one-half of a screw, l and r, Figs. 3 and 50 4, so that when the flat surfaces are brought together the screw is complete, and a nut, m, can be screwed into position, firmly uniting the two sections mechanically and electrically. The section r and the section l are complementary parts, and together form a male screw having a very coarse thread—say four or five turns to the inch. The nut m has a female screw of corresponding thread. I construct one half the cells with connections on 55 one end of each strip b or c of the element P or N, and the other half with connections on the opposite end of the strip b or c of an element, P or N; or I may place connections facing in opposite directions on opposite ends of every strip, or I may screw the connections l and r into place on the strips b and c, so that

the direction in which they face may be changed at pleasure. By either method the desired end is attained, and a perfect, simple, 70 and inexpensive connection for batteries is secured.

What I claim, and desire to secure by Letters Patent, is—

1. In a secondary battery, the combination 75 of two elements or electrodes, one being independently removable with respect to the other, and each composed of a series of plates electrically united, an inclosing-cell therefor, an electrolytic liquid, and means for supporting 80 both elements above the bottom of the cell, consisting of fixed points located on opposite sides of both elements between the upper and lower edges, and points of support located at opposite sides of the interior of the inclosing-cell, substantially as described. 85

2. In a secondary battery, the combination 90 of two elements or electrodes, an inclosing-cell therefor, an electrolytic liquid, and means for supporting both said electrodes above the 95 bottom of the cell, consisting of projections located on opposite sides at or near the central vertical distance thereof and taking against fixed supports within the cell, substantially as described. 95

3. In a secondary battery, the combination 100 of two elements or electrodes, each consisting of a series of plates, an inclosing-cell therefor, an electrolytic liquid, a series of projections on one element located on opposite edges 100 between the upper and lower edges united by a mechanical connection to maintain a fixed distance between the plates, a series of projections on the other element similarly located and resting upon said mechanical connection, and means for supporting said elements upon said projections free from contact with the bottom of the cell, substantially as described. 105

4. In a secondary battery, the combination 110 of two elements or electrodes, each composed of a series of plates, an inclosing-cell therefor, a suitable battery-fluid, a series of projections on opposite sides of both elements near the central vertical distance thereof, 115 strips of conducting material uniting the plates of one element at or near said projections and at a point on the upper edge thereof, strips of conducting material uniting the plates of the second element at points on the 120 upper edge thereof, insulated supports on opposite sides of the inclosing-cell, near its central vertical distance, upon which the projections of the first element rest in position to form a rest for the projections of the second 125 element, and strips of insulating material separating one element from the other, substantially as described.

5. In a secondary battery, the combination 130 of two elements or electrodes, each composed of a series of plates, an inclosing-cell therefor, a suitable battery-fluid, strips of conducting material uniting the plates of one element at one or more points between the upper and

lower edges, also at or near the upper edge, strips uniting the plates of the second element at or near the upper edge, a series of projections on the edges of the second element, insulating-supports upon which the central strips of the first element rest, the projections of the second element resting thereon, and strips of insulating material separating one element from the other, substantially as described.

6. The combination, in a secondary battery, of two elements, each consisting of a series of plates having fixed points of supports between their upper and lower edges, and a support, rest, or frame consisting of two slabs of insulating material located on opposite sides of the cell and held in position with respect to each other by one or more strips, substantially as described.

15 7. The combination, in an electrical connection, of two sections of conducting material, one section being the complementary part of the other, a series of parallel grooves in the surface of each section, the grooves of one 25 registering with the grooves of the other, and a nut for uniting the two sections mechanically and electrically, substantially as described.

8. The combination of two complementary 30 sections of conducting material having a series of parallel grooves united to form a male screw, and a nut having a female screw for mechanically and electrically uniting the two

sections, substantially as and for the purpose described.

9. In an electrical connection, the combination of a battery-terminal carrying a screw-thread, a second terminal carrying a similar screw-thread, and a nut having a corresponding thread for mechanically and electrically 40 uniting both terminals, substantially as described.

10. An electrical connector for batteries, consisting of two sections of conducting material having the form of a cone divided on 45 the plane of its major axis with a helical groove in its curved surface forming a male screw, and a nut having a female screw for uniting the two sections mechanically and electrically combined with a battery-terminal 50 connected to each section, substantially as described.

11. The combination of two sections of conducting material, each forming the terminal of a battery, and each provided with a threaded surface combined with a nut having a threaded contact-surface for mechanically and electrically uniting the two said sections.

Signed at the city of New York, in the county of New York and State of New York, 60 this 14th day of December, A. D. 1888.
